UNITED STATES PATENT OFFICE.

LOUIS M. HOOPER, OF RUTHERFORD, NEW JERSEY.

CLOSET-SEAT.

1,163,149.

Specification of Letters Patent.

Patented Dec. 7, 1915.

Application filed January 28, 1914. Serial No. 814,903.

To all whom it may concern:

Be it known that I, LOUIS M. HOOPER, a citizen of the United States, residing at Rutherford, in the county of Bergen and State of New Jersey, have invented certain new and useful Improvements in Closet- Seats, of which the following is a specification.

My invention relates to new and useful improvements in water closet seats, and particularly contemplates a seat having provision for insuring the user sitting on the same properly so as not to soil the rear of the seat or the bowl upon which the seat is mounted.

The invention consists in the improvements to be more fully described hereinafter, and the novelty of which will be particularly pointed out and distinctly claimed.

I have fully and clearly illustrated my invention in the accompanying drawings to be taken as a part of this specification and wherein—

Figure 1, is perspective view of a seat embodying one form of my invention. Fig. 2, is vertical longitudinal section view through the seat shown in Fig. 1. Fig. 3, is a transverse section view through the seat shown in Fig. 1. Fig. 4, is a plan view of another embodiment of the same invention. Fig. 5, is a section view through the embodiment shown in Fig. 4.

Referring to the drawings by characters of reference, in both of the embodiments adopted herein to exemplify the invention for the purposes of this application, I have shown a well known form of closet seat comprising a rim 1, preferably having a flat under surface 2, adapted to rest upon the upper edge of a closet bowl, shown generally at A, in Fig. 2. The rim has an upper surface 3, preferably rounded transversely, as shown; and said rim forms and surrounds an opening 4 leading to the interior of the closet bowl.

It will be understood that the seat is adapted to be used in connection with any well known form of closet bowl, and be connected thereto in any suitable manner (not shown).

At its rear portion, I provide the seat with means to insure the user sitting properly on the seat and prevent the user from taking a position so far back on the seat as to be likely to deposit soil matter thereon.

In the embodiment shown, this means

preferably consists of an abutment or stop on the back of the seat and carried thereby; said abutment or stop being, as shown in Figs. 1, 2 and 3, in the form of a projection 5 arranged on the upper face of the back portion of the rim and extending upward therefrom above the upper surface of the rim, said projection preferably extending in opposite directions either side of the medium line of the seat extending from front to rear. The projection 5 has a substantially flat, smooth and unbroken upper surface, the rear edge or face of the projection being coextensive and contiguous to the rear edge of the rim of the seat. The width of the projection from front to rear is immaterial, but I preferably form the front edge thereof as being inclined downward, as shown at 6, and as forming the rear wall of the opening 4. The projection is preferably formed at its ends with wings 7, 7, extending forward for a short distance along the sides of the rim, as clearly shown in Fig. 1. The lower edge of the front face 6 of the projection preferably terminates on a line approximately the plane of the upper surface of the seat, and preferably above such line, as shown at 8, so that the front face of said projection and the rear wall of the opening 4 are located above the point where there is likelihood of having soil deposited thereon.

The under face of the rim, at the rear of the latter, and beneath the abutment or stop, is cut away to provide a recess 9 extending transversely of the median line of the seat, said recess being formed with a bottom curved transversely of the seat, and inclined upward from the rear portion of the seat to the bottom edge 8 of the face 6. By this provision the rear of the underface of the seat is elevated and removed from the locality where it is liable to have soil deposited thereon.

In Figs. 1 to 3 I have shown the stop or abutment as being made integral with the seat, in this instance said seat being made of wood or other suitable material, but I desire it understood that the stop or abutment may be made separate from the seat proper, and secured thereto. Such a construction I have shown in Figs. 4 and 5 in which the stop or abutment may be made of porcelain, metal or other suitable material, as shown at 10, and secured in place by any suitable fastening means, as screws or bolts 11. In

this form of the invention the configuration of the stop or abutment may be substantially the same as the form shown in Figs. 1, 2 and 3, and I do not, therefore, deem it necessary to repeat the description of the specific details of construction shown in said figures. It will be seen, that in both constructions shown and described, the front face of the abutment is so located, that, when the user sits, said face is in position to be engaged by the back of the user and thereby prevent movement of the user rearward far enough to take a position where soil is likely to be deposited on the seat.

15 15 What I claim is:

1. A closet seat consisting of a rim surrounding an opening, and an abutment on the rear of the rim having a substantially flat upper surface raised above the plane of

the upper surface of the rim, the front edge 20 of said abutment bounding the rear of said opening.

2. A closet seat consisting of a rim surrounding an opening, and an abutment on the rear of the seat projecting above the 25 plane of the upper surface of the seat, a face of said abutment forming the rear wall of the said opening, the rear edge of said abutment being coextensive with the rear edge of said rim.

30 In testimony whereof I have hereunto signed my name in the presence of two subscribing witnesses.

LOUIS M. HOOPER.
